CARBURETOR FUEL LEVEL CONTROL

Howard W. Linkert, Indianapolis, Ind., assignor to L & L Manufacturing Co. Inc., Indianapolis, Ind., a corporation of Indiana

Application June 7, 1956, Serial No. 589,892

2 Claims. (Cl. 137—426)

This invention relates to a carburetor bowl assembly including an inlet valve and an operating float for controlling the level of fuel in the bowl. The carburetor of which the bowl is a part is of the general type employed in automotive work particularly including motorcycles, automobiles, and the like. The invention is embodied in a structure which is quite sensitive to the maintenance of the desired fuel level in the bowl and also is very readily adjustable to maintain the desired level of fuel in the bowl, even though the construction is subject to extreme vibrations and shifting out positions particularly as encountered in motorcycle handling and traveling.

The structure embodying the invention is further designed to maintain a sealing seating of the inlet valve in the absence of wear of the seat or of the needle valve itself as is generally encountered in usages where the carburetor is subject to considerable vibration.

These and many other objects of the invention will become apparent to those versed in the art in the following description of one particular form of the invention as now best known to me, as illustrated in the accompanying drawing, in which

Fig. 1 is a view in central vertical section through the bowl of the carburetor to which the invention is applied;

Fig. 2 is a view in horizontal section on the line 2—2 in Fig. 1, on a reduced size scale; and

Fig. 3 is a view in vertical section on a reduced scale on the line 3—3 in Fig. 1.

A bowl chamber generally designated by the numeral 10 is formed at one side of the body 11 of the carburetor 10 is formed at one side of the body 11 of the carburetor 10 is formed at one side of the body 11. An inlet fitting generally designated by the numeral 13 is screw-threadedly entered through the floor 14 of the bowl 10 at one side thereof as indicated in Fig. 1, to extend within the chamber 10 by means of a hollow cylindrical stem 15. The fitting 13 has a female screw-threaded end portion 16 from which a passageway 17 extends axially upwardly through the fitting 13 to open into the stem 15.

The fitting 13 is provided with an internal annular shoulder 18 around the bore 17, and immediately above this shoulder 18, the passageway 17 is enlarged to a diameter exceeding that of the shoulder 18 to provide a cylindrical counterbore 19 extending above the shoulder 18 and terminating by an annular shoulder 20. The axial length of the counterbore or chamber 19 is made to be such that its side wall will serve as a guide for the lower end of a cylindrical needle valve 21 immediately above the conical end portion 22 which enters the passageway 17 to seat on the shoulder 18. Thus the length of that bore 19 is kept at a minimum so that when the needle valve 21 is lifted to unseat the conical end 22 from the shoulder 18, and that shoulder 18 is cleared, the cylindrical portion of the valve 21 will be lifted above the shoulder 20 so that fuel entering the fitting 13 and flowing through passageway 17 may discharge into the lower end of the counterbore 19 above the shoulder 20 and flow

2

unrestrictedly outwardly through a port 24 into the bowl chamber 10.

The stem 15 has an internal diameter exceeding the diameter of the valve 21, and a valve guide or bushing 25 is fitted into the upper end portion of the stem 15, to guide primarily the axial travel of the valve 21 in relation to the passageway 17 and the shoulders 18 and 20. This guide 25 terminates above the shoulder 18 to provide an annular chamber 23 across which the fuel may flow from the shoulder 18 through the port 24. The cylindrical counterbore 19 is omitted in the valve mounting heretofore known, and the guiding of the valve 21 is confined to the guide or bushing 25. However, under such a condition the needle valve 21, requiring to be rather loosely guided through the member 25 normally broached to prevent sticking and undue friction will, under severe vibration such as in a motorcycle usage, tend to move laterally particularly by its lower end, under wear particularly of the member 25 by a rocking action, and thus the conical end 22 is normally not presented to the seat 18 to completely contact that seat or shoulder 18 entirely theraround with the result that the shoulder 18 will become worn and out of round in the direction or directions of vibrational movements of the needle valve and when the nose 22 does not seat properly fuel will continue to flow into the bowl 10 tending to increase the level beyond the intended height. In order to overcome that particular problem, the lower end of the needle valve 21 is confined between the shoulder 20 and the wall of the cylindrical portion 19 so as to direct that lower end of the valve 21 axially of the annular shoulder 18 near the seating position.

As indicated in Fig. 1, the lower end of the guiding member 25 is spaced quite a bit above the shoulder 20 so as to leave the said chamber 23 around the needle 21 to give ample flow space for the fuel passing the shoulder 18 in order to permit it to flow readily through the port 24 into the bowl chamber 10.

The upper end of the valve 21 is provided with a neck 27 of a diameter reduced from that of the main part of the valve, and at the upper end of the neck 27 there is provided a roundtop head 28 having an effective diameter approximating that of the valve 21.

A float mounting bracket generally designated by the numeral 29 is made to have the general shape of an upturned leg 30, from the lower end of which leg 30 there extends at a right angle therefrom a foot 31. This foot 31 is provided with a hole 32 therethrough so that the upper end portion of the stem 15 may be slidingly received through the hole 32 and the upper portion of the leg 30 is mounted against a boss 33 provided on the side wall of the upper portion of the cup 12.

The leg 30 is provided with a slot 34 extending longitudinally thereof, and a screw 35 is entered through the slot 34 and screw-threadedly engaged through the boss 33, washers 36 and 38 preferably being provided between the head of the screw 35 and the face of the leg 30, all as indicated in Fig. 1. By reason of the presence of the slot 34, the leg 30 may be adjusted vertically of the bowl chamber 10, the leg portion 31 traveling vertically accordingly up and down the stem 15 so that the leg 30 will not pivot around the screw 35 at any selected position of securement to the boss 33.

The foot 31 has a pair of spaced apart upturned ears 39 and 40 turned upwardly from its sides, and a valve rocker member generally designated by the numeral 41 is rockably carried therebetween on a pin 42 which passes through the ears 39 and 40. In the form herein shown, the pin 42 is held stationary in respect to the ears 39 and 40 to have the rocker 41 rotate about the pin 42 by forming one end of the pin with a flattened head 43 urged against the ear 39 by means of a compression spring 44

bearing between the ear 40 and an outer spring clip 46 engaging the pin 42.

The rocker 41 is provided with a major finger 47 which passes over the head 28 of the valve 21, and is provided with a pair of minor fingers 48 and 49 straddling the neck 27.

The rocker 41 has a post 50 extending from its side opposite to that side from which the fingers 47, 48 and 49 extend. The major portion of the post 50 is cylindrical, but the underside is preferably flattened as at 51.

A float 52 is provided, and preferably it is made out of a cellular, synthetic resin or plastic to have a high degree of buoyancy and also to be nonabsorbent of the fuel. This float 52 is provided with a socket 53 to receive the end of the post 50 and, by reason of the flattened side 51, is held against revolution about the post 50. A rod 54 passes through the float 52 and screw-threadedly engages axially of the post 50 to extend by an outer end 55 from the float 52. The float 52 is then held assembled on the rod 54 and the post 50 by means of a nut 56 of the spring plate type which engages threads on the end 55. Preferably the float 52 in vertical section will be generally cylindrical with the underside having a flat face so that the major portion of the float 52 will be above the rod 54, as best indicated in Fig. 3 where the flat face is designated by the numeral 57. This also means in respect to this construction that the major portion of the float 52 extends above the normal level of the fuel within the bowl chamber 10.

In operation, the float 52 will rock up and down in accordance with the use of fuel from the bowl chamber 10 all in the usual and well known manner, rocking about the axis of the pin 42. In this rocking of the float 52, when the float tends to rock downwardly, the fingers 48 and 49 will bear against the underside of the head 28 tending to lift it so as to lift the conical end 22 from the shoulder 18 and thus admit fuel into the bowl chamber 10. As the fuel level rises in the bowl chamber 10, the needle valve 21 is forced downwardly by the upward travel of the float 52 causing the finger 47 to press down on the head 28 and consequently seat the conical end 22 around the shoulder 18 as the lower cylindrical portion of the valve 21 is guided within the shoulder 20 and slightly downwardly within the cylindrical portion 19 so that the axis of the conical end 22 coincides with the axis of the shoulder 19. If the level in the bowl chamber 10 is not correct for the required feeding the fuel through the carburetor proper, the float 52 may be raised or lowered accordingly by loosening the screw 35 and shifting the leg 30 upwardly or downwardly as may be required along the face of the boss 33 and then tightening the screw 35 to secure that adjustment. In order to effect that adjustment easily, the float 52 may be quickly withdrawn from the rod 54 by taking off the nut 56 to have the float out of the way so that access can be

had to the screw 35. Normally a gauge (not shown) would be used in making this adjustment in the normal procedure by gauging between any fixed points such as between the top face 58 of the cup-like member 12 and the upperside of the rod 54. In making the adjustment, the cup portion 12 would be withdrawn from the body 11 so as to give access to the screw 35 in the present form of the bowl construction, it being entirely obvious that access could be had to the screw 35 through the top of the cup 12 with proper design provided therefor.

Therefore it is to be seen that I have provided a simple mounting construction for both the inlet control valve and the float for operating the valve, and while the invention has been described in more or less minute detail in respect to this one particular embodiment, it is obvious that structural changes may be employed without departing from the spirit of the invention, and I therefore do not desire to be limited to that precise form beyond the limitations which may be imposed by the following claims.

I claim:

1. A carburetor fuel level control combination comprising a fuel bowl having a fuel inlet; a hollow stem extending upwardly into the bowl from said inlet; an annular shoulder within the stem spaced below the stem upper end; a conical-nosed valve longitudinally reciprocable within the stem and seating by its nose on said shoulder; a bracket vertically adjustably mounted within and on a side of said bowl, said bracket having a foot through which said stem extends by a sliding fit; said bracket bearing by an upright portion along the wall of said bowl and having a vertically extending slot through said upright portion; a screw through said slot engaging said bowl selectively retaining the bracket in fixed position along said stem; a float rocker rockably supported by the bracket and engaging said valve; and a float carried by said rocker lifting and lowering the valve upon corresponding travel of the float under influence of changing level of fuel in the bowl.

2. The structure of claim 1 in which said stem has a guide portion immediately about and extending above said shoulder slidably receiving the lower end portion only of said valve above said conical portion and a second valve guide portion spaced from said first guide portion in an upper end portion of the stem.
